UNITED STATES PATENT OFFICE.

MELVIN L. SEVERY, OF ARLINGTON HEIGHTS, MASSACHUSETTS, AND GEORGE B. SINCLAIR, OF GEORGETOWN, MAINE.

TONE-PRODUCING MEANS.

1,199,934.

Specification of Letters Patent.

Patented Oct. 3, 1916.

Original application filed February 20, 1910, Serial No. 545,962. Patent No. 1,137,544, dated April 27, 1915.
Divided and this application filed August 8, 1914. Serial No. 855,885.

To all whom it may concern:

Be it known that we, MELVIN L. SEVERY and GEORGE B. SINCLAIR, citizens of the United States, residing at Arlington Heights, in the county of Middlesex and State of Massachusetts, and Georgetown, county of Sagadahoc, and State of Maine, respectively, have invented certain new and useful Improvements in Tone-Producing

Means, of which the following is a specification.

This invention has for its object the production of musical tones of any desired timbre by apparatus utilizing electric current-interruptions or alternations; the production of musical tones of relatively incommensurate vibrations; and the production of tones of easily changeable timbre.

The present application is a division of our application Serial No. 545,962, which eventuated in Patent No. 1,137,544, dated Apr. 27, 1915 to which reference may be made for any features or details not found herein pertaining to the general or broad principles involved but not claimed herein.

In the accompanying drawings: Figure 1 is an elevation of means for the production of musical tones in accordance with our invention; Fig. 2 is a face view of a rotor and stator wherein the latter is formed with a considerable number of pole pieces, adapted to simultaneously receive and transmit to the translating device, like current alternations, and thereby to reinforce the same; and Fig. 3 is a similar view of a slightly different construction of the same.

In said drawings, the numeral 1 indicates a shaft rotated at uniform speed by an electric motor 2, synchronized by the copper drum 3 revolving between the fields of the electromagnet 4, and by the relay 5 controlling the currents from sources 6 and 7. This means of rotating the shaft at uniform speed is illustrative merely, and may be replaced by any other motor and synchronizing device capable of giving the perfect regulation of speed essential to this class of work.

Upon the shaft 1 we mount one or more rotors 10, formed with teeth, lugs or projections 27, which upon rotation of the shaft travel past and in proximity to inwardly projecting lugs or poles of an encircling

stator 21^b. This stator is provided with coils or windings 39, in which are induced alternating currents as the projections of the rotor approach and recede from those of the stator. These alternating current pulsations are led by suitable conductors to an electromagnet 22, the conductors being electrically connected with the terminals of the coils of the magnet.

Facing a pole of the electromagnet 22 is a string 23, a diaphragm 24, or other body adapted through alternate attraction and release by the magnet, to be thrown into sonorous vibration. In order to cause non-attractive intervals for the recession of the sonorous or vibrating body, the magnet 22 is polarized. This may be effected by employing an extended magnet core, and winding the same with a second coil 25 receiving continuous current from a suitable source 26. It will be seen that under this construction when the coils 22 and 25 receive currents of like polarity, the core will be strongly magnetized and strongly attract the sonorous or vibrating body within its field; but when during the opposite phase of each alternation the two currents are of unlike polarity, the polarity of the core is neutralized and the sonorous body is accordingly released. Consequently, such sonorous body will be alternately attracted and released, its own resilience or tendency to return to normal position causing the swing or movement outward or away from the magnet pole.

As each movement of a tooth or projection 27 of the rotor past a pole-piece of the stator energizes the electromagnet 22 connected therewith, the strength of energization and consequently the loudness of the sonorous vibrations caused thereby, can be multiplied by increasing the number of teeth and pole pieces simultaneously acting to energize such electromagnet. To thus increase the pole pieces it is of course necessary to properly space them so that the angular distances between them shall exactly equal or be some multiple of that between the teeth. So long as there is a non-fractional number of said teeth about the rotor heads, it is easily practicable thus to multiply the pole pieces, but whenever, as in the majority of the strings of a musical instrument, it is necessary to provide pulsations for sonorous

bodies which vibrate incommensurately with respect to others, and incommensurate rotors are accordingly used, it is impossible thus to surround the entire rotor with pole pieces. 5 We have therefore devised means for providing one half the rotor with simultaneously effective pole pieces, and this constitutes the specific subject-matter of the present application, divided out of the parent 10 application, Serial No. 545,962, now Patent No. 1,187,544.

As shown in Figs. 2 and 3, a rotor head 10 is formed with teeth 27, one or more spaces between which are abnormal as at 15 28^a, which space absorbs the fractional tooth that would otherwise occur thereat. Referring to Fig. 2, it will be seen that about such rotor head 10 is located a series of pole pieces equal in number to the teeth 27, and 20 with angular spaces between them, one of the latter, 29, being abnormal in measurement or extent. As is evident on inspection, a number of the teeth and pole pieces will not meet simultaneously with others. We 25 therefore provide an automatically actuated switching means for cutting out of circuit to the electromagnet 22 the windings of the pole pieces which are not met by the teeth at the same instant as are the others. This 30 is done as follows: In continuous contact with the shaft 1 of the rotor is a brush 32 joined by a wire 33 to the electromagnet 22. Fixed on said shaft is a semicircular contact piece 34 in circuit therewith. At diametrically opposite sides of the shaft, and in contact with said contact piece 34 when the latter passes them, are two brushes 36, 37, the brush 36 being joined by wire 38 to one terminal coil 39^a of the set of tandem coils 40 39 wound about the pole pieces 21^b, while the opposite terminal coil 39^b is joined by a wire 40 to the electromagnet 22. The brush 37 is joined by wire 41 to the terminal coil 42^a of the tandem coils 42, and the opposite 45 terminal coil 42^b is joined by wire 43 to the wire 40, and by the latter to said electromagnet. Hence the pole pieces confronted by the abnormal space 28^a will always be cut out from the circuit to the electromagnet 22, 50 while those pole pieces not thus confronted and constituting the other half or group, will be in such circuit throughout every revolution of the rotor.

The construction illustrated in Fig. 3 differs from that in Fig. 2 chiefly in two particulars—the shape of the teeth and pole pieces, and the grouping of the pole pieces in such a manner as to bring an abnormal space at each of two diametrically opposite 60 points in the pole pieces, thereby dividing up the same into two smaller fractions in place of the single large one. Another slight difference lies in the arrangement illustrated in Fig. 3 whereby the loudness of the sonorous vibrations can be reduced at pleasure by

cutting out more or less of the pole pieces as by shifting the brushes 44 of the wires 40, 43 toward the coils 39^a and 42^a, respectively.

In Figs. 2 and 3 for the sake of clearness we have shown but one rotor on each shaft 70 with its opposing stator, but it is manifest that in a musical instrument having a number of musical pitches, we should use a plurality of these rotors and stators, and each shaft 1 would preferably carry a group of 75 rotors. In most instruments there would be several of these groups moving at speeds commensurate with one another. It is clear, therefore, that if commensurate speeds are to produce trains of timed current-impulses, 80 the said trains being incommensurate with one another, there must be at least one break in some of the cycles of impulses. For example, if the speed of the generating device be suited, say, to C, and C be without fractional provision, as it usually would be, then C# revolving either fixedly or commensurate with C, would require fractional provision. We have ascertained by years of 85 experimentation that this fractional provision 90 does not sensibly impair the value of the resulting current waves for use in selective apparatus, nor does it cause the resulting tone of tuned sonorous bodies to lose their 95 full timbre characteristics.

While the production of musical tones is a prominent and perhaps the primary purpose of this invention, it is by no means restricted to such use, but is of somewhat wide application, as, for instance, in ringing 100 systems and the like.

The invention, in other words, consists broadly in the novel means of generating the impulses, and in splitting up a direct electric current into trains of incommensurate 105 periodicities.

Having thus described our invention, what we claim is:—

1. A tone-producing means comprising an electro-magnet; a translating device actuated thereby; a rotor having teeth uniformly spaced thereon except at points where the space is abnormal; a stator surrounding said rotor and having pole pieces spaced to correspond with said teeth, said rotor and stator being provided with suitable means including coils for enabling them to generate and transmit to said electromagnet current alternations from either half of said pole pieces; and switching means whereby the current alternations are generated and transmitted from each half of said pole pieces when said abnormal space is opposing the other half. 110 115

2. A tone-producing instrument comprising a sonorous body; an electromagnet for its vibration; a uniformly rotated rotor having a head provided with equally spaced teeth with the exception that at one point is a space abnormal in length; a stator having pole pieces equally spaced to correspond to 120 125 130 135

said equally spaced teeth; and windings on said pole pieces in circuit with said electromagnet, means being provided for cutting out of circuit temporarily the windings of 5 the pole pieces which fail to correspond with teeth on said rotor.

3. In combination with an electromagnet and a body to be vibrated thereby, a rotor having teeth uniformly spaced throughout 10 the major portion of its circumference but unequally spaced at a point therein; a stator having pole pieces facing the teeth of said rotor, said rotor and stator being provided with suitable means including coils for enabling 15 them to generate and transmit to said electromagnet current alternations from said pole pieces; and switching means whereby the current alternations are generated and transmitted during rotation of the 20 rotor, from pole pieces other than those opposing the abnormal space.

4. In combination with an electromagnet and a body to be vibrated thereby, a rotor having teeth uniformly spaced throughout 25 the major portion of its circumference but unequally spaced at a point therein; a stator having pole pieces facing the teeth of said rotor and likewise equally spaced through the major portion of the series but unequally spaced at a point or points therein; means 30 including coils for enabling said rotor and

stator to generate and transmit to said electromagnet current alternations from said pole pieces; and switching means whereby the current alternations are generated and 35 transmitted during rotation of the rotor from pole pieces other than those opposing the abnormal space.

5. In combination with a body to be vibrated, an electromagnet for effecting its 40 vibration; a uniformly rotatable rotor having a head provided with teeth equally spaced throughout the major portion of the series but unequally spaced at a point therein; a stator having pole pieces likewise 45 equally spaced throughout the major portion of the series but unequally spaced at a point or points therein; windings on said pole pieces in circuit with said electromagnet; and means for cutting out of circuit temporarily the windings of those pole pieces which at the instant are not faced by or 50 opposed to equally spaced teeth of the rotor.

In testimony whereof we have signed our names to this specification in the presence 55 of two subscribing witnesses.
